UNITED STATES PATENT OFFICE.

AMOS F. DIXON, OF NEWARK, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,386,993.

Specification of Letters Patent.

Patented Aug. 9, 1921.

Application filed May 28, 1918. Serial No. 237,070.

To all whom it may concern:

Be it known that I, AMOS F. DIXON, a citizen of the United States, residing at Newark, in the county of Essex, State of New Jersey, have invented certain new and useful Improvements in Telegraph Systems, of which the following is a full, clear, concise, and exact description.

This invention relates to telegraph systems, particularly to printing telegraph systems and is primarily applicable to that class of service wherein the various arms or channels of a multiplex equipment are extended from a central distributing station to a plurality of different outlying and perhaps widely separated stations, at each of which is a local distributor under the control of the central distributor.

Such local distributors are customarily of a type which, in sending out the various current permutations which enter into the formation of the message, provide an interval of no current after each signaling impulse.

The purpose of this invention is to provide a central distributor arrangement which will, in combination with such a system of local distributors, make the maximum use of the main transmission line connecting the two distributing centers.

To this end the invention provides that the central distributors instead of being divided into quadrants, for example, with the segments of each quadrant arranged to control one of the outlying stations, are arranged so that the segments controlling one station overlap or intermesh with the segments controlling another station. By this means the no-current intervals corresponding to one set of signaling impulses are made available for the transmission of the current impulses of another set. Thus the main transmission line is worked to its maximum capacity.

In the accompanying drawing illustrating one embodiment of this invention, a main transmission line 1 terminates at a main distributing station 2, in a differential duplex circuit comprising the differential relay 3 and the artificial line AL. Associated with the relay 3 are two distributors 4 and 5. The distributor 4 controls the transmission to the line 1 of selective impulses received from four outlying stations, A, B, C and D. Distributor 5 controls the distribution to these four outlying stations

of impulses received over the line 1. The arrangement shown requires the use of two line conductors from the main transmitting station to each of the outlying stations. Referring particularly to the distributor arrangement, it will be noted that line conductor 6 which leads to the transmitting equipment T at station B is connected to alternate segments 7 of the distributor 4, while conductor 8 leading to the receiving equipment R at substation B is connected to alternate segments 9 of the distributor 5. Correspondingly, conductor 10 leads to the transmitting equipment at station A, not shown, and is connected to segments 11 on the distributor 4 which are located between the segments 7 and conductor 12, leading to the receiving set of station A, not shown, is connected to segments 13 lying between the segments 9 on distributor 5. In a similar way the transmitting and receiving segments for stations C and D are intermeshed on the two distributors. Thus, as the brush 14, for example, of distributor 4 revolves, it will connect the ring 15 alternately to segments 7 and 11, during one-half of its revolution, and alternately to transmitting leads of the stations C and D during the other half of its revolution. Similarly the brush 16 of distributor 5, in revolving, connects the receiving ring 17 alternately to the segments 9 and 13, during one half of its travel, and during the other half of its travel alternately connects the ring 17 to the receiving leads of stations C and D. Only the station at equipment B is herein illustrated, inasmuch as the equipment at stations A, C and D is a duplicate of that at station B.

The system illustrated is designed to operate a printing mechanism in response to the receipt of various permutations of five impulses of positive or negative polarity. As such impulses are received over the line conductor 1, the relay 3 will move its armature 18 in one direction or the other to connect the ring 17 to positive battery 19 or negative battery 20. If such changes of current occur in synchronism with the passage of brush 16 over contacts 9, these impulses will be effective to actuate one or the other of relays 21 and 22 at station B. These relays control the step-by-step actuation of a distributor 23, relay 21 also controlling the application of current to the selecting magnets 24, 25, 26, 27 and 28 of a local printing

mechanism. The distributor 23 is substantially identical to that described in Danielson's Patent No. 1,215,917 of February 13, 1917, and a detail description of it need not 5 therefore be given here, though some explanation of its operation is perhaps necessary. In the position of the distributor shown, arms 29 and 30 on the reciprocating actuator bar 31 close contacts 32 and 33, respectively. 10 When magnet 34 is energized, the bar 31 moves forward, opening the contacts 32 and 33, and drops down one step on the holding member 35. On the deenergization of the magnet 34, the bar 31 moves back under the 15 influence of spring 36, carrying with it the member 35, which allows a detent 37 also to drop down one step on member 35. The backward movement of the bar 31 brings the arms 38 and 39 in position to close contacts 40 and 41, respectively. In a similar 20 way, for successive actuations of the relay 34, the contacts 42 and 43, 44 and 45, and 46 and 47 will be closed. It will be noted that an operating circuit for relay 34 is completed 25 from battery 50, upon the receipt of each line impulse, whether of positive or negative polarity, this circuit being completed to ground through contacts of relay 21 or relay 22, as the case may be. If the 30 impulse received is of positive polarity, the consequent operation of relay 21 closes contact 51 to connect battery 52 to conductor 53. If, for example, the first impulse is positive, the distributor 23 being in the position 35 shown, the circuit will be completed from battery 52 over conductor 53, by way of contacts 33 of the distributor to selecting magnet 24. If the second impulse is of negative polarity, contact 51 will not be 40 closed. Consequently, the closure of contact 41 by the distributor will not complete an operating circuit for selecting magnet 25. It is thus seen that the selecting magnets 24 to 28 inclusive are operated only upon 45 positive impulses, and are selectively operated, due to the successive closure of contacts 33, 41, 43, 45 and 47 in step with the received signals. Upon the receipt of the fifth selecting impulse, contact 54 will be closed simultaneously 50 with contact 47, and will complete a circuit from battery 55, by way of conductor 56 to ground, through relay 57. Relay 57 operates and closes a holding circuit for itself from battery 58, by way of armature contact 59 of relay 60 and its own armature contact 61. The closure of armature contact 62 completes an operating circuit for restoring magnet 63 from battery 58, by way of contacts 59 and 62 to ground, through the 55 contacts of relay 21 or 22, depending upon which one of these relays has been operated by the fifth selecting impulse. The energization of magnet 63 attracts its armature 64, thereby raising the arm 65 to release 60 the detent 37 and restore member 35 and

the actuator bar 31 to the position shown in the drawing, preparatory to the receipt of a second set of signals. When the armature 64 has completed its stroke, it closes its contact 66 and completes an operating circuit 70 for relay 60, which, on operating, opens the holding circuit of relay 57 at contact 59.

It will be noted that simultaneously with the successive energization of the receiving distributor contacts 33, 41, 43, 45 and 47, 75 the respective transmitting contacts 32, 40, 42, 44 and 46 will have been closed. These transmitting contacts control circuits leading to the movable contact arms 67, 68, 69, 80 70 and 71 of a set of five pole-changer 85 switches which may be selectively operated by any suitable means, not shown, such for example as a keyboard transmitter or a transmitter controlled by a perforated tape, to prepare for transmission various permutations of positive or negative impulses. Thus, as impulses are received at the station B for the actuation of the local printer, a set of selective signals may simultaneously 90 be transmitted over the conductor 6 to distributor 4 at the main distributor station 2, and through distributor 4 sent out on the main line 1 through the duplex circuit above mentioned.

A further consideration of the distributor used at station B will show that there is a time interval between the successive actuations of the local distributor, during which no current is either sent to line 6 or received over line 8. By the arrangement of segments on the distributor here illustrated, this no-current interval is utilized to transmit to and receive from station A, signal impulses corresponding to other messages. It is thus seen that while the conductors 100 leading from the main station to the branch stations are not worked to their maximum capacity, the main line 1 which is in most cases an expensive toll line, is worked to its 105 full capacity.

What is claimed is:

1. A telegraph system comprising a main distributor station, independent transmitting and receiving rotary distributors at said station, a plurality of outlying stations, current impulse distributors at each of said outlying stations driven by character signaling impulses sent from the main distributor station, and a circuit extending from each of said main station distributors to each 115 of said outlying stations, one of said circuits being connected directly to alternate segments of said transmitting distributor and the other of said circuits being connected directly to alternate segments of said receiving distributor.

2. A telegraph system comprising a main distributor station, independent transmitting and receiving distributors at said station each being provided with a plurality 120

of insulated segments, a main line circuit, a relay included in said main line circuit and responsive to incoming signals, a plurality of outlying stations, an extension circuit connected directly to alternate segments of the main station receiving distributor extending to each of said outlying stations, current impulse distributing apparatus at each of said outlying stations actuated by

signaling impulses transmitted from the 10 main distributor station, and a circuit extending directly from the distributor at the outlying station and connected directly to alternate segments of the main station transmitting distributor.

15

In witness whereof, I hereunto subscribe my name this 22nd day of May, A. D. 1918.

AMOS F. DIXON.
